J. P. CONGER.

Evaporating Pan.

No. 10,564.

Patented Feb. 28, 1854.

UNITED STATES PATENT OFFICE.

JOHN P. CONGER, OF NEWARK, NEW JERSEY.

IMPROVEMENT IN SALT-KILNS.

Specification forming part of Letters Patent No. 10,564, dated February 28, 1854.

To all whom it may concern:

Be it known that I, JOHN P. CONGER, of Newark, in the county of Essex and State of New Jersey, have invented a new and useful Improvement in Making Salt; and I hereby declare the following to be a full and clear description thereof, reference being had to the drawings herewith presented, which drawings constitute a part of said description.

The nature of my improvement consists in the construction of a kiln with small fires at each end, so as to apply the fire near to the boilers, having but a short arch over each fire, and conducting the flues immediately to the kettles.

The common mode of making salt is to have a long kiln, say, one hundred feet, (more or less,) with one large fire at one end, and an arch of brick extending along between it and the kettles, to prevent melting the kettles, whereas I have a short arch at each end just over the fire, and then conduct the flue direct to the pans. I also have a cistern of water placed above the kiln through which the flame is conveyed with tubes, for the purpose of heating the water before it comes into the pans.

In the drawings, Plate 1 is a view of the kiln. A is the front side. B B are the kettles. C is the arch supporting the kettles. E is the fire-flue; D, the chimney; F, the tubes passing through the trough or cistern G, furnished with holes I, to draw the water into each pan.

Plate 2 is a view of the same, having the top removed in order to show the interior arches, L, inside walls, K, and center wall, M, extending the length of the kiln. N is a hole to let the heat pass under the kettles.

Plate 3 is a sectional end view, showing the arch P, the grate R, ash-pit T, and chimneys O O.

I am aware that tubes have been used for the purpose of heating water for other purposes; therefore I do not claim the invention of tubes, but the application of them to the making of salt I believe has never been made before; and by means of my new kiln I am able to make more in any given time and with a vast deal less amount of fuel.

What I claim, and desire to secure by Letters Patent, is—

The arrangement of a salt-kiln having two small fires with short arches over the grates at each end, and the flues thereof meeting in the middle of the kiln and passing into tubes leading through the feed-trough, placed immediately above and along the kiln, in the manner and for the purposes set forth.

In testimony whereof I hereto subscribe my name in presence of two witnesses.

JOHN P. CONGER. [L. s.].

Witnesses:

D. W. BALDWIN,
HANNAH BALDWIN.
